CLAIM

The ornamental design for a payphone base, as shown and described.

DESCRIPTION

FIG. 1 is a top, front and right side perspective view of a payphone base according to the present design; FIG. 2 is a top plan view thereof;

FIG. 3 is a front elevational view thereof;

FIG. 4 is a left side elevational view thereof, the right side being the mirror-image;

FIG. 5 is a bottom plan view thereof;

FIG. 6 is a rear elevational view; and,

FIG. 7 is a perspective view of a second embodiment of that shown in FIG. 1.

*Fig. 2.**Fig. 3.**Fig. 4.**Fig. 5.**Fig. 6.*

Fig. 7
